LASTING MACHINE

Lester S. Macdonald, Beverly, Mass., assignor to
 United Shoe Machinery Corporation, Flemington, N. J., a corporation of New Jersey

Application October 5, 1949, Serial No. 119,591

7 Claims. (Cl. 12—8.7)

1

This invention relates to lasting machines, and more particularly to means for operating wipers to last end portions of shoes in such machines. The invention is herein shown as embodied in a modification of a toe-lasting machine constructed as disclosed in an earlier application of mine, Serial No. 11,912, filed on February 28, 1948, but it will be understood that it is not limited to this illustrative embodiment.

The machine shown in the above-mentioned application is provided with toe-embracing wipers which are advanced lengthwise of the last and are closed widthwise of the last around the toe preparatory to the wiping of the upper heightwise of the last and are thereafter further advanced and closed to wipe the marginal portion of the upper inwardly over an insole on the last. After the wiping of the upper over the insole, tackers which are moved independently of the wipers to positions over the shoe are operated to drive tacks through openings in the wipers to secure the upper in lasted position. To advance the wipers as above described a wiper carrier on which they are supported is moved lengthwise of the last by a cam-operated lever connected to the carrier by special means on the lever whereby the limit of the movement of the wipers lengthwise of the last prior to the wiping of the upper heightwise of the last may be varied without affecting the limit of their movement thereafter over the insole.

The construction above described has been found to operate satisfactorily under most conditions. In operating, however, on very heavy upper materials the resistance of the upper to the advance of the wipers in wiping its marginal portion inwardly over the insole may cause the mechanism for operating the wiper carrier, by reason of its construction, to spring slightly and thereby to prevent the wipers from arriving at the intended limit of their movement lengthwise of the last. In the organization shown this may undesirably affect the alignment of the tackers with the openings in the wipers through which the tacks are driven. The present invention accordingly provides, in addition to means for normally advancing the wipers lengthwise of the last to a predetermined limit of movement in the wiping operation, means for insuring completion of the movement of the wipers to the limit thus determined regardless of the resistance of the upper materials. In the construction shown this additional means comprises a pair of cams arranged to act positively on the wiper carrier independently of the above-mentioned lever

2

near the end of the wiper-advancing movement of the lever to complete the movement of the carrier if conditions are such that it is not moved to the required limit by the lever.

5 The novel features of the invention, including various novel details of construction and combinations of parts, will now be more particularly described with reference to the accompanying drawings and thereafter pointed out in the

10 claims.

In the drawings,

Fig. 1 is a view in right-hand side elevation of the upper portion of the machine in which the invention is shown as embodied;

15 Fig. 2 is a view partly in right-hand side elevation and partly in vertical section, showing the wiper-operating mechanism;

Fig. 3 is mainly a plan view showing the wipers and a portion of their operating mechanism;

20 Fig. 4 is a detail view in right-hand side elevation of a portion of the structure shown in Fig. 2;

Fig. 5 is a view also in right-hand side elevation of another portion of the structure shown in Fig. 2, with the parts in different positions; 25 and

Fig. 6 is a vertical sectional view illustrating how the tacks are driven through openings in the wipers.

In view of the disclosure in the above-mentioned application only as much of the machine as it is necessary to refer to for an understanding of the present invention will be herein described in detail. For wiping the upper around the toe end of the last heightwise of the last and

35 for thereafter wiping its marginal portion inwardly over an insole on the last the machine is provided with a pair of toe-embracing wipers 2 detachably mounted on wiper holders 4 which are supported on a wiper carrier 6 under a cover

40 plate 8 on the carrier and are each provided with a downwardly extending curved rib 10 (Fig. 2) lying in a correspondingly curved guideway 12 (Fig. 3) in the carrier to guide the wipers for closing movement widthwise of the shoe, the shoe 45 being supported and controlled by means fully disclosed in the above-mentioned application. The wiper carrier 6 is supported near its front end for movements to advance and retract the wipers bodily lengthwise of the last and shoe on

50 a pair of links 14 (Figs. 1 and 2) which are spaced apart widthwise of the shoe and are pivotally connected at their upper ends to lugs on the carrier, the lower ends of the links being supported by means hereinafter described. Near its rear end the wiper carrier is further supported by a

lever 16 through which it is moved in directions lengthwise of the shoe, this lever being mounted to swing about a shaft 18 supported on the frame of the machine. At its lower end the lever 16 carries a roll 20 engaged by a groove cam 22 on a cam shaft 24. The upper end of the lever 16 is not connected directly to the wiper carrier 6, but is connected indirectly thereto through means which will now be described. Pivotedly mounted on a stud 26 on the upper end of the lever is a bell-crank lever 28 having a rearwardly extending arm 30 pivotally connected to the upper end of a rod 32 which extends downward loosely through a bore 34 formed in a projection 36 on the lever 16. Between this projection and a head 38 on the upper end of the rod is a compression spring 40, and threaded on the lower end of the rod are nuts 42 which hold the spring normally under compression. Pivotedly mounted on a stud 44 on an upwardly extending arm 46 of the bell-crank lever 28 is another bell-crank lever 48 having an upwardly extending arm 50 pivotally connected by a rod 52 to the rear-end portion of the wiper carrier 6 and supporting this portion of the carrier. A rearwardly extending arm 54 of the bell-crank lever 48 has thereon a roll 56 engaged by a groove cam 58 formed by two plates 60 and 62 (Fig. 4) secured on an arm 64. This arm is fast at its lower end on the shaft 18 which is mounted to turn in bearings in the frame. Through a rod 66 and other mechanism not herein shown but fully disclosed in the earlier application the arm 64 is movable to adjust the cam 58 in directions lengthwise of the shoe but is held stationary during the operation of the machine on the shoe.

When the lever 16 is operated by its cam 22 to advance the wiper carrier and the wipers lengthwise of the shoe, it carries the two bell-crank levers 28 and 48 bodily with it and in this manner imparts the movement to the wiper carrier, the position of the bell-crank lever 48 with respect to turning movement about the stud 44 being determined by the stationary cam 58. When the wipers are advanced and closed about the toe prior to the wiping of the upper heightwise of the last, an inclined portion *a* (Fig. 4) of the cam 58 engages the roll 56 and thereby swings the bell-crank lever 48 in a counterclockwise direction with reference to Fig. 2 about the stud 44, thus imparting to the wiper carrier and the wipers additional forward movement the extent of which is determined by the adjustment of the cam 58. That is, adjustment of the cam in a rearward direction serves to increase the amount of forward movement imparted to the wipers, since more of the inclined portion *a* of the cam is effective to swing the bell-crank lever 48 about the stud 44 before the lever 16 comes to a stop, and conversely adjustment of the cam in a forward direction reduces the amount of swinging movement imparted to the bell-crank lever. This construction permits the positions of the wipers lengthwise of the last at the time when they wipe the upper heightwise of the last to be readily varied in accordance with the character of the upper materials. When the lever 16 is further operated by its cam, after the wiping of the upper heightwise of the last, to cause the wipers to wipe the marginal portion of the upper at the end of the toe inwardly over the insole, the bell-crank lever 48 may or may not be further swung about the stud 44 by the inclined portion *a* of the cam 58, depending upon the adjustment of the cam. Before the wiping of the

upper inwardly over the insole is completed the roll 56, whatever may be the adjustment of the cam, arrives in a position where it is engaged by a portion *b* of the cam which is concentric with the axis of the shaft 18. Accordingly, the limit of the forward movement of the wipers over the insole is invariable regardless of the adjustment of the cam. Normally the spring 40 does not yield, and accordingly the bell-crank lever 28 maintains a fixed relation to the lever 16 throughout the operation of the machine. In case, however, the wipers in their forward movement encounter abnormal resistance, the spring may yield to permit the wipers to stop while the lever 16 continues its movement, thus avoiding any danger of damage to the machine or to the shoe.

The previously mentioned links 14 which support the wiper carrier 6 near its front end are pivotally connected at their lower ends to short arms 68, one of which is shown in Fig. 1 and the other in Fig. 2, these arms being fast on a rock-shaft 70 on which is also secured an arm 72 provided with a roll 74 engaged by a groove cam 76 a fragment of which is shown in dotted lines in Fig. 2. It will be understood that by this mechanism the wiper carrier is swung upwardly about the axis of the rod 52 to cause the wipers to wipe the upper heightwise of the last and is later swung downwardly to increase the pressure of the wipers on the marginal portion of the upper over the insole.

For imparting to the wipers closing movements widthwise of the shoe the wiper holders 4 are connected through links 78, more fully shown and described in the earlier application, to a slide 80 (Fig. 2) guided for movements lengthwise of the shoe on the wiper carrier 6. Secured to the slide 80 is a rearwardly extending rod 82, and confined by a nut 84 on the rear end of this rod is a member 86. Between this member and the slide 80 is a spacing sleeve 88 on the rod 82. Pivotally connected to opposite sides of the member 86, as more fully shown in the earlier application, are forwardly extending links one of which is shown in dotted lines at 90 in Fig. 2, the front ends of these links being pivotally connected to the bifurcated upper end of an arm 92 of a bell-crank lever 94 pivotally mounted at 96 on lugs extending downwardly from the wiper carrier 6. A rearwardly extending arm 98 of this bell-crank lever is connected by an adjustable link 100 to an arm 102 fast on a rock-shaft 104. Also fast on this rockshaft is an arm 106 provided at its lower end with a roll 108 engaged by a groove cam 110 on the cam shaft 24. It will thus be seen that by the action of the cam 110 the bell-crank lever 94 is operated to impart wiper-closing movement to the slide 80 in proper time relation to the advancing movements of the wipers lengthwise of the shoe. As explained in the earlier application, the limits of the closing movements of the wipers are positively determined.

After the marginal portion of the upper has been wiped inwardly over the insole by the wipers and while it is held by the wipers it is secured to the insole by the driving of tacks through openings 112 in the wipers, as illustrated in Fig. 6. For this purpose there are provided two tackers 114, one for each wiper, and means whereby they are operated to drive the tacks successively in different locations along the margin of the shoe bottom, as fully disclosed in the earlier application. The tackers are carried from initial re-

tracted positions forwardly and downwardly to positions where they will aline properly with the openings 112 in the wipers by a tacker support 116 (Fig. 1) which is pivotally mounted at its rear end for swinging movement heightwise of the shoe on members 118, one of which is shown in Fig. 1, these members being slidably movable lengthwise of the shoe on the top of the frame. The tacker support 116 is thus movable bodily lengthwise of the shoe in addition to being mounted to swing heightwise of the shoe. Both the bodily movement and the swinging movement are imparted to the tacker support by a pair of crank arms 120 fast on a shaft 122 mounted to turn in bearings on a top frame plate 123, the crank arms being pivotally connected to the lower ends of members 124 which extend upwardly into openings in the support and on which the front end portion of the support rests. Fast on the shaft 122 is a pinion 126 engaged by another pinion 128 which is engaged by the teeth of a gear sector 130 fast on the upper end of a lever 132. This lever is mounted to swing about a rod 134 on the frame and has on its lower end a roll 136 engaged by a groove cam 138 on the cam shaft 24. By this cam the lever is swung in a counterclockwise direction with reference to Fig. 1 at the time in the cycle of operations of the machine when the wipers wipe the upper inwardly over the insole to move the tackers into positions to begin the tack-driving operations.

As thus far described the machine herein shown is of the same construction as disclosed in the earlier application, and this construction has been found to operate satisfactorily under most conditions. In view, however, of the character of the means provided for imparting the wiper-advancing movement to the wiper carrier 6, comprising the lever 16 and the two bell-crank levers 28 and 48 arranged in series, it may happen that in operating on very heavy upper materials the resistance of the upper to the advancing movement of the wipers in wiping its marginal portion inwardly over the insole will cause the mechanism for operating the wiper carrier to spring slightly and thereby prevent the wipers from arriving at the normal limit of their movement lengthwise of the last. This may prevent the upper from being wiped as far inwardly as desired and may also undesirably affect the alinement of the tackers 114 with the openings 112 in the wipers. To insure against such undesirable results the construction herein shown includes two bell-crank levers 140 fast on a rockshaft 142 mounted to turn in a bracket 144 secured to the top frame plate 123 underneath the plate. A downwardly extending arm 146 of each of these levers is connected by a link 148 to the rod 52 which, as hereinbefore explained, connects the arm 50 of the bell-crank lever 48 to the wiper carrier 6. Mounted on a forwardly extending arm 150 of each bell-crank lever 140 is a roll 152 arranged to be engaged by a cam 154 fast on the shaft 122. When the wiper carrier is moved forwardly lengthwise of the last by the lever 16 and the parts connecting it to the rod 52 on the carrier, this rod acts through the links 148 to swing the bell-crank levers 140 idly in clockwise directions with reference to Fig. 2 and thereby to swing upwardly the forwardly extending arms 150 of these levers. When the wiper carrier is at the normal limit of its forward movement the arms 150 are in engagement with stop faces 156 on the front ends of plates 158 secured on the top frame plate 123, as illustrated in Fig. 5. If

conditions are such that because of the resistance of the upper materials the movement of the wiper carrier to its normal limit is not quite completed by the action of the lever 16, the cams 154, after moving into engagement with the rolls 152, act on the arms 150 near the end of the tacker-positioning movement of the shaft 122 to complete positively the movement of the carrier. Insurance is thus afforded that regardless of the resistance of the upper the wipers will be moved lengthwise of the last to the required positions.

Having described the invention, what I claim as new and desire to secure by Letters Patent of the United States is:

- 15 1. In a lasting machine, wipers for wiping the marginal portion of an upper around an end of a last inwardly over an insole on the last, power-operated means for normally advancing said wipers lengthwise of the last to a predetermined limit of movement in the wiping operation, a member separate from said wipers and arranged to be moved idly by said power-operated means, and additional positively acting power-operated means including a member movable into engagement with said first-named member for insuring the completion of the movement of the wipers to said predetermined limit regardless of resistance of the upper materials to the action of said first-named means.
- 20 2. In a lasting machine, wipers for wiping the marginal portion of an upper around an end of a last inwardly over an insole on the last, a wiper carrier mounted for movement to carry said wipers lengthwise of the last, power-operated means for normally advancing said wiper carrier lengthwise of the last to a predetermined limit of movement in the wiping operation, a member arranged to be swung idly by said power-operated means, and additional power-operated means constructed and arranged to act positively on the wiper carrier through said member independently of said first-named means to insure the completion of the movement of the carrier to said predetermined limit regardless of resistance of the upper materials to the action of said first-named means.
- 25 3. In a lasting machine, wipers for wiping the marginal portion of an upper around an end of a last inwardly over an insole on the last, a wiper carrier mounted for movement to carry said wipers lengthwise of the last, a power-operated lever for normally advancing said wiper carrier lengthwise of the last to a predetermined limit of movement in the wiping operation, a member movable idly by said lever, and additional power-operated means including a cam movable into engagement with said member to insure the completion of the movement of the carrier to said predetermined limit regardless of resistance of the upper materials to the action of said lever.
- 30 4. In a lasting machine, wipers for wiping the marginal portion of an upper around an end of a last inwardly over an insole on the last, a wiper carrier mounted for movement to carry said wipers lengthwise of the last, a lever, a cam for operating said lever to advance the wiper carrier normally lengthwise of the last to a predetermined limit of movement in the wiping operation, another lever movable idly by said first-named lever, and additional positively acting cam means for operating said other lever to insure completion of the movement of the wiper carrier to said predetermined limit re-
- 35 70

gardless of resistance of the upper materials to the action of said first-named lever.

5. In a lasting machine, wipers for wiping the marginal portion of an upper around an end of a last inwardly over an insole on the last, a wiper carrier mounted for movement to carry said wipers lengthwise of the last, a lever connected to said wiper carrier, means for operating said lever to advance the wiper carrier normally lengthwise of the last to a predetermined limit of movement in the wiping operation, a pair of bell-crank levers also connected to the wiper carrier, and cams for operating said bell-crank levers to insure the completion of the movement of the wiper carrier to said predetermined limit regardless of resistance of the upper materials to the action of said first-named lever.

6. In a lasting machine, wipers for wiping the marginal portion of an upper around an end of a last inwardly over an insole on the last, a wiper carrier mounted for movement to carry said wipers lengthwise of the last, a power-operated lever for advancing the wiper carrier normally lengthwise of the last to a predetermined limit of movement in the wiping operation, other levers connected to the wiper carrier to be swung by the movement of the carrier, and power-operated means for further swinging said other levers to

10
15

complete the movement of the carrier if its movement to said predetermined limit is not completed by said first-named lever.

7. In a lasting machine, wipers for wiping the marginal portion of an upper around an end of a last inwardly over an insole on the last, a wiper carrier mounted for movement to carry said wipers lengthwise of the last, a power-operated lever for advancing the wiper carrier normally lengthwise of the last to a predetermined limit of movement in the wiping operation, other levers connected to the wiper carrier to be swung by the movement of the carrier, and power-operated cams arranged to act on said other levers after such swinging movements thereof to complete the movement of the carrier if its movement to said predetermined limit is not completed by said first-named lever.
